RADIO TUNING APPARATUS

Adolph A. Thomas, New York, N. Y., assignor to
 Radio Corporation of America, New York, N. Y.,
 a corporation of Delaware

Application April 28, 1932, Serial No. 607,917

7 Claims. (Cl. 250—20)

This invention relates to the art of radio reception, and one of its objects is to provide novel clock-controlled mechanism for automatically tuning in one or more preselected stations at certain predetermined intervals. I further provide a recording device automatically set in operation at the right moment for recording the broadcast of any desired station, whether tuned in by hand or by clock-controlled connections. This tuning and recording control may be effected at a distance from the radio receiver, which is electrically connected with a small box containing the clock-controlled apparatus of my invention. It sometimes happens that people would like to make a record of an unusual piece of radio broadcast, such as an address by a prominent person, or a song by a renowned singer. While provision for radio recording has heretofore been made, it has been necessary for a person to watch the clock for tuning in the station to be recorded, and to start the recording mechanism by hand. Experience has shown that people frequently forget about tuning in this or that station at a certain time, and so they miss at least part of the desired program. To obviate this, it has previously been proposed to operate radio receivers by clock-controlled tuners, but these do not provide for automatic recording of the received broadcast. The disadvantages of that are obvious. Even if a desired station is brought in by clock-tuning, the person who wants a record of the reception may not be on hand to connect the recorder when the program starts. One of the main objects of my invention is to assure the recording of a radio broadcast without attention by the operator; in fact, even if the latter should not be at home. To give an illustration: Let us suppose that at nine o'clock in the evening a certain station will broadcast a program which a person wants to record. He finds, however, that circumstances prevent his being at home at that hour. Nevertheless, by the use of my invention, he need only manipulate a finger piece before leaving the house, and precisely at nine o'clock the desired station will be tuned in and the recording mechanism will be automatically set in operation to record the received broadcast. When that particular piece of broadcast is concluded, all electric circuits are automatically opened, so there is no waste of current. A simple switch enables a person to cut the recording mechanism in or out, as desired. Aside from the clock-controlled radio-recording feature of my invention, I have provided a

remote clock-tuner of simplified and compact structure, by means of which a certain number of stations can be selected in advance to be tuned in automatically at certain intervals. In a preferred form of my invention, a box containing a clock has a series of small dials representing each a certain station. These dials may conveniently be arranged round the face of the clock, and not more than five or six will usually be necessary. Each of these station dials is divided into quarter-hours, and has a pointer which can be set by hand to any time. To bring in any one of the preselectable stations at a certain moment, a person need only set the pointer of the associated dial to indicate the required time, and the rest is automatic. The station-selecting pointers are preferably operated by knobs which can be pulled out and pushed in a slight distance. When a knob is in one position, the time control for that particular station is on; and in the other position of the knob, the time control is off. This makes it a very simple matter to regulate the time control for each station individually.

Another feature of my invention comprises means for predetermining the length of time during which the radio receiver shall be in operation, irrespective of the indications on the station-selecting dials. Thus, if a person selects one or more stations to be clocked between the hours of 8 and 11 in the evening, and he wants the receiver turned off at 11:30, when the last broadcast concludes, he need but set a "Time out" pointer at 11:30. When that time arrives, all circuits are automatically opened and stay that way. This arrangement makes it possible for a person to enjoy radio reception at night while lying in bed till he falls asleep, for the receiver will turn itself off at the right time.

The foregoing and other novel features and practical advantages of my invention will be fully understood from a detailed description of the accompanying drawings, in which—

Fig. 1 illustrates the front panel of a clock-controlled radio tuner embodying my invention;

Fig. 2 represents a sectional side-view on line 2—2 of Fig. 1;

Fig. 3 shows a transverse section approximately on the broken line 3—3 of Fig. 2;

Fig. 4 is a fragmentary sectional view on line 4—4 of Fig. 1;

Figs. 5 and 6 are enlarged fragmentary views showing certain contacts of the clock-tuner in different positions;

Fig. 7 shows diagrammatically a practical form of reversing switch adapted for use in the

circuit of the reversible motor that operates the tuning shaft; and

Fig. 8 is a diagram of circuit connections between the radio receiver, the recording mechanism and the remote control box.

A suitable box or casing B contains clock-operated switch devices adapted to control the tuning elements of a radio receiver and also the driving motor of an associated recording mechanism. The apparatus in box B is so compact that the box need be no bigger than shown in Figs. 1, 2 and 3, and may be even smaller. The control box B may be embodied in a radio cabinet, or it can be built as a separate portable unit (like a mantle clock) located in any convenient place remote from the receiver and electrically connected thereto by a cable. The size, shape and ornamental appearance of control box B may be varied to suit the builder's or the buyer's taste, and for simplicity I have shown a plain rectangular box having a front panel 10, a back 12, sides 13, a top 14, and a bottom 15. It is desirable to make these parts of insulating material, like wood or bakelite, to obviate the use of separate insulation for the electric contacts in the box. A clock K is attached to the outside of back 12 by screws 16 or otherwise, whereby the clock is easily removable for inspection or repair without disturbing the inside mechanism.

Any approved make or style of clock may be used, whether spring-wound or electric. The front panel 10 carries a clock-face 17, and the hands 18 and 19 are connected to the clock by an arbor or spindle 20 and a hollow shaft 21. The minute hand 18 is attached to the spindle 20, and the hour hand 19 is fixed to the hollow shaft 21, through which the spindle passes. A hub 22 on the front panel 10 forms a bearing for the rotary nested members 20 and 21. If the panel 10 is molded of composition material, the bearing 22 may be an integral projection.

The rear shaft 21 has fixed thereon a pinion 23, which may be secured by a set-screw 24 or otherwise. The pinion 23 is wide enough to be in permanent mesh with a series of gear wheels 25, which in this instance are six in number, because it has been assumed that six different stations can be individually selected by means of the control box B. The gear wheels 25 are idlers mounted on studs or pins 26, which are screwed into the back plate 12 of the box. Since the pinion 23 rotates clockwise, all the idlers 25 rotate in the opposite direction, as indicated by the arrows a in Fig. 3. Each idler gear 25 meshes with a pinion 27, and these pinions are rotatably mounted on fixed shafts 28 carried by the back plate 12 of the control box. The pinions 27 may conveniently be formed as integral teeth on sleeves 29, through which the supporting shafts 28 pass, and which therefore provide a wide bearing surface to insure a smooth and easy movement. This will be clear by looking at Fig. 2. The shafts 28 pass through hubs 30 in back plate 12 and are secured against rotation by cross-pins 31 or otherwise.

On each of the six sleeves 29 is fixed an insulating disk 32, and to facilitate distinguishing between these disks I have added the letters A to F to the numeral 32 of each disk. A convenient way of mounting the disks 32 on their respective sleeves 29 is to provide the latter with a reduced extension 33 over which the disks are inserted and locked in place by a set-screw 34. The disks 32 can be molded of bakelite, or they can be cut from sheet stock. Since the pinions 27 are of

the same size as the central driving pinion 23, it is evident that the insulating disks 32 all rotate clockwise at the same speed as pinion 23, which makes one revolution every hour. In the broader aspect of my invention, any other practical form of driving connection may be employed between the hour shaft 21 of clock K and the insulating disks 32. In Fig. 3 the disk 32D is for the most part broken away to show certain parts behind it, and the dash-dot line 32' is intended to indicate the periphery of the part broken away.

The front panel 10 of the control box carries a series of rotary knobs or buttons 35, which are differentiated from each other by suffix letters A to F respectively. Each knob 35 is attached to (or forms an integral part of) a sleeve 36, which is rotatably and slidably mounted on the aligned shaft 28, as shown in Fig. 2. An insulating disk 38 is fixed to the inner reduced end 37 of each sleeve 36, and for convenience I have distinguished these disks from each other by the suffix letters A to F respectively. A set-screw 39 holds each disk 38 in correct angular position on its sleeve 36. It is thus clear that each knob or button 35 operates one of the insulating disks 38. That is to say, the knob 35A operates disk 38A, knob 35B operates disk 38B, and so on for the other four knobs with which the control box B is provided. From Fig. 2 it is seen that each shaft 28 carries a pair of insulating disks 32 and 38, the first being clock-driven and the second being manually adjustable by the associated button or knob 35. I might explain that in Fig. 3 the disks 38C, 38D and 38F do not appear because the lower part of section line 3-3 in Fig. 2 is behind those disks. However, it is easy to understand that those three disks are directly in front of disks 32C, 32D and 32E, respectively, on shafts 28.

Each finger piece 35 carries or otherwise actuates a pointer 40 arranged to cooperate with a circular clock dial 41, which is marked off into quarter-hours, finer divisions being usually unnecessary. The dials 41 are distinguished from each other by the suffix letters A to F, respectively, for convenience of description. Each dial 41 is supposed to represent a certain station, and six of these stations are indicated in Fig. 1 by their call letters. The station dials 41 may be molded of insulating material in the form of rings attached to the front panel 10 by screws 42 or otherwise. Each dial ring 41 has a central recess 43 in which the time-setting pointer 40 operates. When any one of the knobs 35 is pushed in, the pointer 40 is at or near the bottom of recess 43, as shown in Fig. 2. However, when the knob is pulled out to the dotted line position 35', the pointer 40 is approximately in line with the adjacent dial 41, as indicated by the dotted outline 40' in Fig. 2. The outer position of pointers 40 brings them practically into the plane of the markings on dial 41, so that it is easy to obtain strictly accurate time settings of the pointers. The sliding movements of knobs 35, the purpose of which will be explained in due course, are limited inwardly by the annular shoulder 44 on each knob, and outwardly by the inner end 45 of the hubs 46 in which the sleeves 36 are mounted. By looking at Fig. 2, it is evident that the inward movement of each knob 35 is stopped when the shoulder 44 strikes the bottom of recess 43 of the dial ring 41. The outward movement of any knob 35 is stopped when the associated disk 38 strikes the inner end 45 of

the supporting hub 46. In actual practice the extent of the axial movements of the station-selecting knobs 35 is only a small fraction of an inch. The sleeves 36 may be mounted on shafts 5 28 and hubs 46 with sufficient friction to be firmly held in either axial position. I may, however, in some cases employ separate retaining means, such as a spring-pressed ball 47 carried by each sleeve 36 and arranged to snap into either one 10 of a pair of grooves 48 and 49 in the associated shaft 28. By providing the knobs 35 with a peripheral rib 35a (see Fig. 2), it is easy to grasp them for pulling out.

Each insulating disk 32 carries a peripheral contact ring 50 and a contact finger 51 projecting axially from the front face of the disk. A simple way to connect the contact finger 51 electrically to the peripheral ring 50 is by means of a metal bolt or rivet 52, which passes through the disk and 20 through extensions 53 and 54 on the contact members 50 and 51 respectively. This construction is most clearly shown in the enlarged fragmentary views of Figs. 5 and 6. The bolt or rivet 52 also serves the additional function of securing 25 the parts 50 and 51 to the insulating disk 32, although separate fastening screws may be used if found necessary or desirable. The extension 53 may be a radial strip formed integral with the peripheral contact ring 50, and the same applies 30 to the extension 54 of the contact finger 51. The latter is preferably a finger of spring metal formed on its free end with a small knob or button 55, which is easily produced by displacing the metal. In like manner, each insulating disk 35 carries a peripheral contact ring 56 and a contact finger 57 electrically connected with the ring by a metal bolt or rivet 58. Since the contact members 56 and 57 of disk 38 are substantially identical with the contact members 50 and 51 of disk 32, the previous description of parts 50 and 40 51 is fully applicable to parts 56 and 57 without the need of repetition.

The insulated contact fingers 51 and 57 of each pair of disks 32 and 38 are so mounted that, when 45 the disk 38 is in its inner position (that is, when the connected knob 35 is pushed in), the two contact fingers remain out of engagement with each other during the rotary movement of either one of the disks. This is clear from Fig. 5. When, 50 however, a knob 35 is pulled out, the connected disk 38 is moved to such position that the button-shaped ends 55 and 59 of the spring contacts 51 and 57 are brought into the same radial plane. Consequently, during the rotation of disk 32 by 55 the clock, the spring finger 51 will at the proper moment engage the spring finger 57 of the manually adjusted disk 38, as clearly shown in Fig. 6. The contact fingers 51 and 57 are sufficiently resilient to give way easily and thereby not interfere with the rotation of disks 32 and 38. It is 60 only necessary to the operation of the device that the contact fingers 51 and 57 remain in engagement for a few seconds to close certain circuits, as will be explained in the description of the circuit diagram illustrated in Fig. 8. It is assumed 65 that the disks 38 are held in any manually adjusted position with sufficient friction to prevent their being radially displaced by the engagement of contact fingers 51 and 57.

70 An insulated arm 60 is associated with each pair of disks 32 and 48, and each arm carries a pair of resilient contact fingers or brushes 61 and 62. The insulated arms 61 may be integral extensions of small plates 63, which are easily attached to the back panel 12 of the box by screws

64. The parts 60 and 63 may be molded of composition material or the like. Each contact finger 61 is in pressure engagement with the conducting ring 50 of the associated disk 32, and each contact finger 62 engages the conducting ring 56 of 5 the adjacent disk 38. The spring fingers 62 are wide enough to remain in engagement with the contact rings 56 during the axial adjustment of disks 38. The contact fingers 61 and 62 are secured to their respective supporting arms 60 by 10 set-screws 65 or in any other practical way.

The front panel 10 of the control box carries an additional pair of rotary and slidable knobs 66 and 67 provided with pointers 68 and 69 arranged to cooperate with time dials 70 and 71, 15 respectively, which are divided into quarter hours, like the station-selecting dials 41. What has previously been said about the construction and mounting of knobs 35 and dials 41 applies fully to knobs 66-67 and dials 70-71. The 20 knobs 66 and 67 are carried by (or form part of) sleeves 72 and 73 rotatably mounted on fixed shafts 74 and 75, respectively, which are supported at their rear ends by the back plate 12, as described for shafts 28. A pinion 76 rotatable 25 on shaft 74 meshes with an idle gear wheel 77, which is journalled on a pin or stud 78 carried by the back plate 12. The idler 77 also engages the pinion 27 of disk 32C, which (as already explained) is driven by the hour shaft 21. The 30 shaft 75 carries a pinion 79 in mesh with an idle gear wheel 80 mounted on a stud 81, which may be screwed into the back plate 12, like the studs 28. The idler 80 also engages the pinion 27 of the clock-driven disk 32E, whereby the pinion 79 35 rotates clockwise.

The pinions 76 and 79 are attached to (or integral with) sleeves 76' and 79' rotatable on their respective shafts 74 and 75, and those sleeves carry insulating disks 82 and 83, which may be 40 similar to the disks 32 in construction and mounting. In Fig. 3 the disk 82 is partly broken away, as indicated by the circular outline 82', to show certain parts behind it. Since the pinions 76 and 79 have the same number of teeth 45 as the pinions 23 and 27, it is evident that the disks 82 and 83 rotate clockwise at the rate of one revolution an hour. The insulating disks 82 and 83 carry peripheral contact rings 84 and 85, which are always engaged by a pair of contact fingers 86 and 87 mounted on insulated arms 88 and 89. What has been said for the construction and mounting of arms 60 may be considered applicable to arms 88 and 89. The disk 82 carries a forwardly projecting contact finger 90, 55 which is electrically connected to the contact ring 84. Similarly, the disk 83 has a contact finger 91 electrically connected to the peripheral ring 85. It may be assumed that the previous description of the mounting and connection of 60 contact members 50 and 51 on disks 32 applies also to the contact members 84 and 90 on disk 82 and to the contact members 85 and 91 on disk 83.

The rotary and slidable sleeve 72 on shaft 74 65 (see Fig. 4) carries an insulating disk 92, which has a peripheral conducting ring 93 and a rearwardly projecting contact finger 94 electrically connected to the ring. The ring 93 is always engaged by a contact finger 95 mounted on the 70 insulated arm 88. Similarly, as shown in Fig. 2, the rotary and slidable sleeve 73 on shaft 75 carries an insulating disk 96, which has a peripheral metal ring 97 and a contact finger 98 projecting rearwardly therefrom. A spring fin- 75

ger 99 on arm 89 presses against the ring 97, which is electrically connected to the contact finger 98. It may be assumed that the two pairs of co-operating contact fingers 90-94 and 91-98 are 5 constructed and arranged like the cooperating contacts 51 and 57 on each pair of aligned disks 32 and 38. That is to say, when the knobs 66 and 67 are pushed in, the contacts 90 and 94 on disks 82 and 92, and the contacts 91 and 98 on disks 83 and 96, are all inoperative. When the knob 66 is pulled out and the pointer 68 turned to the desired time indication, the contact 94 is moved into the path of the clock-driven contact 90 (see Fig. 4), and when those two 10 contacts engage they close an electric circuit whereby the radio receiver and the recording mechanism are automatically turned on at the time selected by pointer 68. The automatic cut-out of the receiver and the recorder is predetermined by pulling out the knob 67 and setting the pointer 69 to the desired time. The circuits controlled by the contacts associated with the knobs 66 and 67 will be explained in due course.

Referring to Fig. 1, the front panel 10 of box B also carries an extra push button 100 for tuning in any station at any time independently of knobs 35, a volume-control knob 101, a pair of switch-operating members 102 and 103, and two signal lamps 104 and 105. While the lamps 20 are not absolutely necessary, it is usually desirable to have them for the purpose of visually informing the operator whether the electric power for the radio receiver and for the recording device is on or off. The rotary knob 101 25 operates a contact arm 106 which moves over a resistance element 107 for regulating the volume of reproduction. There are several ways of connecting the rheostat 106-107 in the radio circuit for volume control, but I need not go into 30 specific details, because such connections are well understood in the radio art and form no part of my invention. The signal lamps 104 and 105 are preferably of different colors for distinction, that is, the light shines through differently colored lenses mounted on the front of 35 the box. For example, the lamp 104 may be red to indicate that the electric power for the receiver is on, and the other lamp 105 may be green to let the operator know that the recording device is in operation. The switch-operating members 102-103 are shown for convenience as snap-over levers, but any other kind of suitable 40 finger-piece may be used.

In Fig. 8 the dotted outline 108 represents diagrammatically the remote control box B, and all parts within that outline are supposed to be mounted in the box. Hence, all wires crossing the dotted outline 108 represent conductors in the electric cable that operatively connects the 45 box B with a radio-receiver R and a recording outfit S. The system of Fig. 8 requires at most only eighteen wires in the connecting cable, which may be in the form of a flat flexible band easy to place anywhere. Of course, these connections 50 may be concealed within walls, like electric house-wiring. I have spoke of eighteen wires in the connecting cable, but only sixteen of these are indicated in Fig. 8, because I have omitted the two wires that would lead from the volume-control- 55 rheostat 106-107 to the radio receiver R. To simplify the circuit diagram, the time-setting and station-selecting disks 38 have been omitted, and the contacts 57 carried by those disks are 60 diagrammatically represented as rotary contact arms, which are distinguished by the suffix letters 65 A to F for the different stations herein selected by way of example. The finger piece 102 is connected to a cam 109 pivoted at 110, and this cam actuates a spring switch arm 112, which is normally out of engagement with the associated stationary contact 113. A hump 114 on switch arm 112 presses against the tip of cam 109 and holds the latter in either operated position against a pair of fixed stops 115 and 116. When the finger piece 102 is thrown against stop 116, the tip of 70 cam 109 rides on to the peak of hump 114 and holds the spring arm 112 pressed against contact 113. In the same way does the pivoted cam 117 of the finger piece 103 control the position of the spring switch arm 118 with respect to its contact 119. I want it understood that the members 112-113 and 118-119 represent any kind of suitable switch.

The rectangular outline R is supposed to stand for any approved type or make of radio receiver, and no description thereof is necessary. For convenience I have separately indicated a loud-speaker L, which is connected to the output of the receiver and is usually (but not necessarily) housed in the radio cabinet itself. The electrical connections from the antenna to the input of the radio receiver have been omitted, and I have shown only a pair of conductors 120 and 121 leading to the receiver for supplying all necessary parts with electric power. If the radio receiver 20 R is of the type operated from the house-lighting system, connections are made by inserting a plug 122 into a suitable socket in the lighting circuit, and the leads 123-124 of the plug may for the 25 purposes of this description be considered as the source of power for the receiver R and the recording outfit S. The conductor 121 goes directly from the power main 124 to the radio receiver, but the other conductor 120 is connected to the lead 123 through the switch 112-113. To 30 this end the lead 123 is connected to switch arm 112, and the associated contact 113 is connected to wire 125, to which the conductor 120 is connected at 126. The signal lamp 104 is included in wire 125, and it may be shunted by an equivalent resistance 127 to prevent breaking of the circuit if the lamp should accidentally burn out. When the switch arm 112 is closed by moving the finger piece 102 on box B to "on" position, the power circuit is completed through conductor 35 123, closed switch 112-113, wires 125 and 120, through radio receiver R, wire 121, and back to the return main 124.

It is generally known that every radio receiver 40 has adjustable tuning means, which at the present time are almost universally in the form of variable condensers mounted on one or more shafts. For simplicity I have assumed that the radio receiver R has a rotary shaft which operates the variable tuning elements by rotating 45 through a predetermined arc in either direction. This rotary tuning shaft is diagrammatically indicated in Fig. 8 by the dotted line 128. It should be understood that the tuning shaft 128 and all 50 associated parts are shown removed from the radio set R in Fig. 8 for the sake of clearness. The shaft 128 carries a series of cam disks 129, which are differentiated by the suffix letters A to F, and which are supposed to represent the same stations as the remote-control knobs 35 55 (A to F) and the contacts operated thereby. The disks 129 are so fixed on shaft 128 that the angular position of the cam point 130 of each disk 60 corresponds to a certain preselected station.

The cam disks 129 may be stamped or cut from 70

a sheet of insulating material like bakelite; and each disk controls a pair of switches, which are shown diagrammatically as contacts 131—132 and contacts 133—134. The contacts 131 and 133 are movable spring arms arranged to cooperate with the adjacent stationary contacts 132 and 134 respectively. To facilitate the tracing of circuits, I have differentiated between the switch arms 131 and 133 by using suffix letters A to F. The switch arms 131 and 133 associated with each cam disk 129 are connected by an insulating pin 135, so that they always move as a single member. Or, the switch arms of each pair may be arranged side by side and engaged simultaneously by the cam point 130 of the associated disk 129. It will be noticed that the switch members 131—132 are normally closed, whereas the switch members 133—134 are normally open, for a reason that will presently appear. The normal position of switch arms 131 and 133 may be obtained by the inherent set or tension of the spring metal composing the arms, but separate restoring means may be used if preferred. In practice, all the switches 131—132 and 133—134 may be mounted on a single insulating bar arranged parallel with shaft 128 and adjacent thereto.

The recording apparatus S is diagrammatically indicated by a rectangular outline, and it will not be necessary to show or describe the structural details of any particular device, because such details form no part of my invention. Recording devices of various kinds for home use are well known in the art and are obtainable in the market. For example, certain recording outfits employ a blank phonograph disk or cylinder, usually provided with a plain spiral groove in which a recording stylus cuts a sound track. Other recording machines operate on the optical principle and utilize light variations to photograph sound tracks on a film. A third type of recording device uses a magnetic wire or tape to record the sound magnetically on the well-known Poulsen principle. It will therefore be understood that the part S in Fig. 8 represents any type or make of recording mechanism suitable for use in my invention, and the only thing I need to specify about this mechanism is that it has an electric motor 136 for driving the recording element, whether it be a wax disk, a roll of film, a spool of magnetic wire, or any other member adapted to receive recordings. So it may be assumed that, when the motor 136 is energized, the recording mechanism operates, and it stops when the motor circuit is broken or when the motor is otherwise disconnected from the shaft that drives the recording element. The operative circuits for the device S are not shown and need not be described, for they are well known to all acoustic engineers. Two conductors 137 indicate diagrammatically an operative connection between the output of the radio receiver R and the input of the recording device S, whereby the broadcast program coming through the receiver is automatically recorded while being at the same time reproduced through the loudspeaker L. Of course, the latter can be cut out, if desired, during the recording operation, but people usually want to hear what is being recorded.

The tuning shaft 128 may be operated by hand in the usual way when the remote control box B is not being used, but to effect remote tuning I connect the shaft to an electric motor 138. It will be understood that the shaft of this motor is connected in properly reduced ratio to the tuning shaft 128 in any practical way. In the

present instance it has been assumed that the shaft 128 turns through half a revolution to cover the tuning range. Hence, when the shaft 128 is operated by motor 138, it is necessary to reverse the rotation of the shaft automatically at each end of its arc of travel. This may be accomplished in any practical way, as by an automatically reversing transmission connection between the motor shaft and the tuning shaft, or by a suitable reversing switch in the motor circuit. In the latter case it is necessary to use a reversible motor, and by way of example I have shown the motor 138 as of the shunt-wound reversible type operating on direct current. Another kind of reversible motor obtainable in the market is an induction motor run by alternating current. It is immaterial what kind of power unit is used to rotate the tuning shaft 128 either continuously in the same direction (when the tuning elements of the radio receiver permit that) or alternately in opposite directions through a certain arc.

In the present instance, the armature winding 139 of tuning motor 138 is connected to a reversing switch indicated as a whole by W. As represented diagrammatically in Fig. 8, this switch comprises a pair of contact arms 140—141 pivoted at points 142—143 and connected by an insulating pin 144. Two pairs of contacts 145—146 and 147—148 are associated with switch arms 140—141. The opposite ends of the armature winding 139 are connected by wires 149 and 150 to contacts 145 and 146, respectively. The wire 149 (or contact 145) is connected by wire 151 to contact 148, and a wire 152 goes from contact 146 (or wire 150) to contact 147. Thus it is clear that, when the switch arms 140—141 are in full-line position as shown in Fig. 8, the current flows through the armature 139 in one direction; and when those switch arms are in the dotted-line position 140'—141', the armature current is reversed. There is no change of current flow in the shunt field winding 153 of the motor. In the circuit diagram of Fig. 8 it should be assumed that the reversing switch 140—141 is automatically operated as the shaft 128 reaches either end of its arc of travel. One way of accomplishing this automatic operation of reversing switch W is illustrated in Fig. 7, which I will describe before taking up the circuits of Fig. 8.

Referring to Fig. 7, the tuning shaft 128 carries a gear wheel 154 in mesh with a pinion 155 mounted on a shaft 156. The transmission ratio between these gears is 1:2, so that a half revolution of the gear wheel 154 rotates the pinion 155 a full turn. The pinion 155 has a pin 157 arranged to engage the free end of an arm 158 pivoted on a stud 159. A second arm 160 is also mounted on stud 159 and is connected to the upper arm 158 by a contracting coil spring 161. The ends of this spring are attached to the pivoted arms 158 and 160 at the points 162 and 163 respectively. The line of tension of spring 161 is to one side or the other of the pivot axis 159, so that the spring always tends to rock the arms 158 and 160 toward each other. The free end of the upper arm 158 projects into the path of pin 157 on pinion 155, whereby that arm is rocked through a small arc limited by two fixed stops 164 and 165. If we assume for the moment that the pinion 155 is turning counterclockwise, as viewed in Fig. 7, the pin 157 will strike the left side of arm 158 and throw it against the right stop 165. This clockwise rocking of arm 158 moves the tension line of spring 161 to the right of pivot axis 159.

158, whereby the lower arm 160 is quickly snapped to the right, or counterclockwise. When the pinion 155 turns clockwise after the arm 158 has been moved against the top 165, the pin 157 at the 5 end of one revolution of the pinion will move the arm 158 counterclockwise and the tensioned spring 161 will snap the lower arm 160 to the left. The snap-over movements of the pivoted arm 160 are utilized to operate the contact arms 140—10 141 of the reversing switch W previously described in connection with Fig. 8. For this purpose the free end of arm 160 moves between the opposing humps 166 and 167 on switch arms 140 and 141. When the actuating arm 160 presses against the 15 hump 166 on switch member 140, the circuit is closed through the armature 139 as follows: Assuming the point 142 to be connected with the positive terminal of an electric power circuit, the current goes through the arm 160, contact 145, 20 wire 149, through the armature winding 139 in a certain direction, wires 150 and 152, and across the closed switch contacts 147 and 141 to the point 143, which is supposed to be connected to the return conductor of the circuit. When the pivoted 25 arm 160 is snapped by coil spring 161 against the hump 167 of switch arm 141, the contacts 146 and 148 are engaged by the movable switch arms 140—141 and the current now flows through the armature winding in the reverse direction as follows: From point 142, contact arm 140, contact 30 146, wire 150, through the armature winding 139 in a direction reverse to the previous flow of current, wires 149 and 151, and across the closed contacts 148 and 141 to the point 143. Since the 35 current through the shunt field winding 153 of the tuning motor 138 is not reversed with the reversal of the armature current, it follows that the motor automatically reverses its operation every time the arm 160 is snapped from one position to the other 40 by the tensioned spring 161.

Attention is called to the fact that the snap-over movements of the pivoted arm 160 produce instantaneous opening and closing of the switch, whereby arcing is avoided. It should be assumed 45 that the switch arms 140—141 remain in firm pressure engagement with their respective contacts until the actuating arm 160 strikes the opposite hump 166 or 167, as the case may be. This means that there is no movement of the switch members 140—141 during the preliminary movements of the pivoted arm 160 when the tension line of spring 161 starts moving from one side to the other of the pivot axis 159. Whatever flutterings may occur at the free end of arm 160 50 prior to the actual snap-over swing, the closed position of the switch members 140—141 is not affected until the free end of the arm actually strikes the opposite hump 166 or 167 and moves the switch members 140—141 to the other position. 55 This construction produces a reversing switch free from arcing, which is very desirable in practice. It should also be noted that, although the pin 157 does not complete a full revolution from one position to the other before it strikes one 60 side or the other of arm 158, the fact is that the actual snap-over movement of arm 160 occurs just as the pinion 155 reaches the end of a complete revolution. This insures the automatic reversal of tuning shaft 128 every time it completes 65 half a revolution. Manifestly, the operation of reversing switch W by the pinion 155 can take place at the end of a complete revolution of tuning shaft 128, if the tuning devices of a particular type of radio receiver so require. Although the 70 75 reversing switch W above described has certain

practical advantages, I want it understood that my invention is not limited to any particular form of reversing means for the motor-driven tuning shaft 128.

Returning now to Fig. 8 for the circuit connections, we see that the rotary contacts 57 are all connected to a common conductor 168, which in actual practice may be a short metal bar, or even a single binding post, conveniently mounted in box B and electrically connected to the brushes 10 or contact fingers 62. The common conductor 168 is connected by wire 169 to wire 125 at point 170. The push button 100 is mounted on (or otherwise operates) a switch arm 171 to which the wire 125 is connected. The switch arm 171 15 may simply be a spring finger which normally holds the button 100 pushed out and which is movable into engagement with a stationary contact 172. A wire 173 connects the contact 172 with the point or terminal 142 of switch arm 140. 20 A wire 174 connects the service main 124 with one end of the field winding 153 of tuning motor 138, and the other end of this winding is connected to the stationary contact 172 at point 175. From this point a conductor 176 leads to point 177 of a 25 common conductor 178 to which all the stationary contacts 132 are connected in parallel. The conductor 178 may be a short contact bar or a single binding post in the radio cabinet. Each contact brush or finger 61 in the remote control box B 30 is connected by a wire 179 to a corresponding switch arm 131 in the radio receiver. For distinction I have marked the different wires 179 with the suffix letters A to F. Thus it will be seen that contact finger 61A is connected by wire 179A to 35 switch arm 131A; contact finger 61B is connected by wire 179B to switch arm 131B, and so on for the other contact fingers 61 and switch arms 131.

A wire 180 leading from the service conductor 124 is connected in parallel to all the switch arms 40 133 in the radio receiver, and the contacts 134 of these switch arms are connected to a common conductor 181 which goes to the terminal 182 of the recording mechanism S. The other terminal 183 of the recording mechanism is connected by 45 wire 184 to the switch contact 119 in the remote control box. As previously mentioned, the recording mechanism S contains an electric motor 136 for driving the recording element and other movable parts, and this motor is therefore connected 50 in the supply circuit through the switch 118—119. The signal lamp 105 may be included in conductor 181, and is preferably shunted by an equivalent resistance 185 to prevent interference with the 55 operation of the system by an accidental burning out of the lamp. The movable switch arm 118 operated by the finger piece 103 is connected by wire 186 to wire 125. It should be noted that the hand switch 118—119 is in series with the switches 133—134 in the radio receiver. This means that, 60 even when the finger piece 103 is moved to "on" position to close the switch arm 118, the recording mechanism is not placed in operative condition until one of the switches 133—134 has been closed by the associated cam disk 129 on the tuning shaft 128. It may be assumed that the circuit wires 181 and 184 which lead to the recording mechanism S energize not only the driving motor 136 but also all other electrical parts contained 65 in the device. This will be understood without elaboration.

Still referring to Fig. 8, the switch-operating cam 109 carries an arm 187, to the ends of which are attached two magnetic plungers 188 and 189 movable into and out of their respective coils 70 75 75

190 and 191. One side of coil 190 is connected to conductor 123, and the other side of the coil is connected by wire 192 to contact 94 of the hand-operable disk 92. In the actual device, the wire 5 192 will be connected to the contact finger or brush 95 which engages the peripheral ring 93 of disk 92. For simplicity the parts 92, 93 and 95 have been omitted in the diagram of Fig. 8. One side of the other solenoid coil 191 is connected to 10 wire 125, and the other side of that coil is connected by wire 193 to contact 98 of the hand-operable disk 96. It will therefore be understood that the rotary contacts 94 and 98 in Fig. 8 are adjustable to any time indication by the knobs 66 15 and 67, respectively, of Fig. 1. The contact brushes 86 and 87 associated with disks 82 and 83 are connected by wires 194 and 195 to the service main 124. If the solenoid coils 190 and 191 are designed to operate at low voltage, suitable resistances 196 and 197 may be inserted in wires 192 and 193. It is clear that, when the coil 190 is energized, the cam 109 is rocked clockwise to close the switch arm 112, which remains firmly closed even after the circuit of coil 190 is broken. When the 20 other coil 191 is energized, the pivoted cam 109 is rocked the other way to allow the spring arm 112 to snap into normal open position. It should be noted that the solenoid mechanism connected with cam 109 does not at any time interfere with 25 the operation of the switch by means of the finger piece 102.

To explain the operation of the clock-controlled tuning system and recording mechanism as above described, let us assume that a person wants to record the program that will come in over station 30 WOR beginning at 1:45 P. M. To bring this about, it is only necessary to perform the following simple manipulations on the remote control box B: The knobs 35A and 66 are pulled out and 35 their respective pointers 40 and 68 are turned to the hour 1:45, as shown in Fig. 1, and the recording switch 103 is thrown to "on" position. It may be assumed that these preliminary manipulations are done some time prior to 1:45 P. M. 40 The radio switch 102 is left in "off" position, because it is supposed that the radio receiver will not be used until the hour of 1:45. When that time arrives, the clock-driven contact 51A of disk 32A engages the contact 51A which was previously set to the 1:45 time indication by the knob 35A. At the same time the clock-driven contact 90 of disk 82 engages the contact 94 which was set by the knob 66. The engagement of contacts 90 and 94 energizes the solenoid coil 190 through 45 the following circuit: Conductor 123, coil 190, wire 192, across the closed contacts 94 and 90, collector brush 86, and through wire 194 to the return lead 124. The energizing of coil 190 pulls down the magnetic plunger 188 and rocks the cam 109 to close the switch arm 112. The closing 50 of this switch energizes the tuning motor 138 as follows: From service conductor 123 across the closed switch 112—113, wire 125 to point 170, wire 169, common conductor 168, across the closed contacts 51A and 51A, collector brush 61A, wire 179A, across the closed switch 131A—132 to point 177 of conductor 178, wire 176 to point 175, from there through the armature 139 and field coil 153 of motor 138, as previously explained, and finally 55 through wire 174 to the return lead 124.

It should be noted that the recording mechanism S has not yet been energized, because the desired station has not been tuned in. However, it takes only a few seconds for the motor 138 to 70 rotate the tuning shaft 128 until the cam 130 of

disk 129A strikes the hump of switch arm 131A, and moves the latter out of engagement with contact 132. Thereupon the circuit of motor 138 is broken and the shaft 128 stops instantly in correct tuning position for the selected station 75 WOR. When the switch arm 131A is thrown open by the cam disk 129A, the connected switch arm 133A is at the same time moved against the associated contact 134, whereby the power supply leads 181 and 184 of the recording mechanism S 10 are included in circuit as follows: From main conductor 123, closed switch 112—113, wires 125 and 186, closed switch 118—119, wire 184, terminal 183, from there through the driving motor 136 and all the other electrical parts in the recording 15 device, then to outgo terminal 182, wire 181 and lamp 105, across the closed switch contacts 134—133A, and through wire 180 to the return conductor 124. The recording mechanism S is therefore in operative condition to record the broadcast coming from station WOR at 1:45 P. M. The recording of the received program goes on automatically while it is being reproduced through the loudspeaker L of the radio receiver. The recording mechanism may be in the same cabinet with 20 the receiver or mounted in a separate casing placed at any convenient point.

It will not be necessary to trace the circuits for the other stations represented by the knobs 35B to 35F, because those circuits will be readily understood from Fig. 8 by the skilled electrician. If a person wants to have several stations brought in automatically at predetermined moments, it is only necessary to pull out the corresponding knobs 35 and set their respective pointers to the various 35 times when the stations start the desired programs. For example, in Fig. 1, if all the knobs 35 are pulled out, station WJZ will come in at 12:30, station WOR at 1:45, station WEAF at 3:00, station WGBS at 6:00, station WABC at 7:45, and 40 station WRNY at 10:45. It is assumed that these times are all between 12:00 noon and 12:00 midnight. Since programs of quality are not broadcast between 12:00 midnight and morning, there is no need to divide the dials 41 into twenty-four 45 hours, although such a refinement may be adopted if desirable in any particular case. When several stations are selected by pulling out the knobs 35, each station will be automatically brought in at the time set, so that the operator pays no attention to the remote control box after the preliminary manipulations have been accomplished. In this way the recording mechanism S will automatically record the broadcast programs of the different stations in the order in which they 50 came in.

If the receiver R and the recording mechanism S are to be shut off at the conclusion of a certain broadcast, the knob 67 is pulled out and set to indicate the time at which the electric power is 60 to be cut off. Let us suppose that the radio receiver (either alone or with the recording mechanism) is to be turned off at 11:30. For this purpose a person need only pull out the knob 67 and turn the pointer 69 to the hour of 11:30, and 65 when that moment arrives, the clock-driven contact 91 of disk 83 engages the contact 98 which was set by the pointer 69. The circuit is now closed through solenoid coil 191 as follows: conductor 123, closed switch 112—113, coil 191, wire 70 193, across the engaging contacts 98 and 91, collector brush 87, and through wire 195 to the return lead 124. The energizing of coil 191 rocks the cam 109 into the position shown in Fig. 8 to open the switch arm 112. All circuits for the 75

radio receiver and the recording mechanism are now opened and stay open until closed again by hand or by means of the "time-in" knob 66.

The purpose of push button 100 on the remote control box B is for tuning in any station at any time independently of the knobs 35 which represent certain preselected stations. The push button 100 is used, for instance, when a person does not desire any particular station but merely wants to go hunting for a suitable program, no matter where it comes from. In that case, it is assumed that the knobs 35, 66 and 67 are all pushed in, whereby the time mechanism is rendered inoperative. The finger piece 102 is thrown 15 to "on" position to close the power circuit of the radio receiver, but the circuit of the tuning motor 138 will not be closed until the button 100 is pushed in and is held in that position. The circuit of motor 138 is closed as follows: Conductor 20 123, across the closed switch 112-113, wire 125 across the closed switch 171-172, from there in parallel through the armature winding 139 and field coil 153 of motor 138, and through wire 174 to the return lead 124. As long as the button 25 100 is held in, the motor 138 continues to rotate the tuning shaft 128 slowly until the operator is satisfied with a certain program, whereupon the push button 100 is released and the radio receiver remains in tuning position for the station 30 last heard. To record a program obtained by the hunting button 100, I provide a separate switch indicated as a whole by V at the bottom of Fig. 8. When the switch members 198-199 are closed, the recording circuits are closed through 35 conductor 123, closed switch 112-113, wires 125 and 186, closed switch 118-119, wire 184, through the recording mechanism S, wire 181 to point 200, closed switch 198-199, and through wire 180 to return lead 124. The finger piece 201 may 40 be mounted on the front panel of the remote control box B.

The individual tuning knobs 35 can also be used for tuning in at any moment the stations represented by those knobs. Let us say, for instance, 45 that it is 6:15 by the clock dial 17, and that a person wants to tune in station WJZ at that moment, it is only necessary to pull out the knob 35D and turn its pointer to the hour of 6:15, whereby the contacts 51D and 57D of the associated disks 32 and 38 are brought instantly into 50 engagement and close the circuit through the tuning motor 138 in the manner previously described. The rounded buttons 55 and 59 on the spring fingers 51 and 57 (see Figs. 5 and 6) permit the spring finger 57 to be moved axially as 55 well as radially into engagement with the rounded end of spring finger 51. The contacts 51 and 57 remain in engagement long enough for motor 138 to move the shaft 128 into preselected tuning 60 position. The slideable adjustment of knobs 35 permits any one of the individual stations indicated on panel 10 to be disconnected from the control of the clock mechanism. Whenever a knob 35 is pushed in, the station represented by 65 that knob is not subject to clock control. The dialing button 100 is needed only to bring in stations other than those represented on the front panel of the remote control box. Under our present system of chain broadcasting, a person 70 in any locality can get all the good programs from three or four stations, so that not more than that small number of dials 41 will generally be necessary on the remote control box.

Although I have shown and described a certain 75 form of apparatus and system for remote con-

trol and recording of radio broadcast, I want it understood that the broad features of my invention may be embodied in other ways than herein set forth. Many changes and modifications are doubtless possible within the scope of the ap- 5 pended claims.

I claim as my invention:

1. The combination of a radio receiver having variable tuning means, clock-controlled mechanism for automatically operating said tuning 10 means at a predetermined time to tune in a preselected station, said mechanism having a plurality of finger pieces operatively disconnected from the mechanism, there being a finger piece for each station to be preselected, means for 15 mounting each finger piece for independent rotary and axial adjustments by hand, means controlled by a manual rotary adjustment of any finger piece to select the time at which the corresponding station shall be automatically tuned 20 in, and means controlled by a manual axial adjustment of any finger piece to render said clock-controlled mechanism ineffective to tune in the corresponding station.

2. The combination of a radio receiver having 25 tuning mechanism, a device for recording broadcast reception coming through said receiver, a box located at a distance from said receiver, a plurality of clock-controlled switches in said box, electric connections between said switches and 30 said tuning mechanism for preselecting one or more stations to be tuned in at predetermined intervals, manually controlled means for operating said tuning mechanism independently of said clock-controlled switches to tune in any station at any time, a manually operable switch member for rendering said recording device operative to record the broadcast of a station tuned in by said manually controlled means, means for automatically setting said recording device in 35 operation when said mechanism is in tuning position for a selected station, said last-mentioned means being operable independently of said switch member, manually operable means carried by said box for rendering said last-mentioned 45 means inoperative, whereby the recording device is kept out of operation, a loudspeaker operatively connected with said receiver, and means for simultaneously operating said recording device and said loudspeaker, which remains operative 50 when said recording device is rendered inoperative by said manually operable means.

3. A clock-controlled tuning mechanism for 55 radio receivers, comprising in combination a plurality of dials representing each a certain station, a pair of rotary electric contacts associated with each dial, one contact of each pair being manually adjustable and the other contact being operated by clock-work, a single clock-driven shaft for simultaneously operating all of said other 60 contacts, whereby the manual adjustment of the first-named contact of any dial determines the time at which said contact engages the associated clock-driven contact, means whereby the engagement of a pair of said contacts automatically 65 tunes in the station represented by the corresponding dial, and means for moving the manually adjustable contact of any pair out of the path of the associated clock-driven contact to render the corresponding station dial ineffective 70 for clock-controlled tuning, said last-mentioned means being manually operable at any time independently of the clock.

4. In a remote control box for radio receivers having tuning mechanism, the combination of 75

a clock having its face on the front panel of said box, a plurality of dials mounted on said panel around said clock face, each dial representing a certain station and bearing time notations, a manually turnable pointer associated with each dial, an electric contact operated by each pointer, a rotary electric contact associated with each of said pointer-operated contacts, transmission connections whereby all of said rotary contacts are simultaneously driven by said clock, electric connections between said contacts and said tuning mechanism for automatically operating the latter at predetermined intervals as determined by the positions of said pointers, and means for moving the manually adjustable contact of any pair out of the path of the associated clock-driven contact to render the corresponding station dial ineffective for clock-controlled tuning, said last-mentioned means being manually operable at any time independently of the clock.

5. The combination of a radio receiver having variable tuning means, a rotary shaft for operating said tuning means, electric driving means for said shaft, a set of normally closed switches operatively associated with said shaft and representing each a certain station, a set of clock-controlled switches representing the same stations as said first set of switches, each clock-controlled switch comprising a rotary clock-driven contact and a manually adjustable contact, a rotatable and slidable spindle on which each manually adjustable contact is mounted, a finger piece for adjusting said spindle rotatably and axially, the axial adjustment of said spindle moving the supported contact into and out of the path of the associated clock-driven contact, electric connections whereby the closing of a clock-controlled switch at a predetermined moment automatically energizes said electric driving means, and means controlled by said shaft for automatically opening one of said first-named set of switches when the shaft is in tuning position for the station represented by the closed clock-controlled switch and the opened shaft-controlled switch.

6. A clock-controlled tuning mechanism for radio receivers, comprising in combination a plu-

rality of dials representing each a certain station, a pair of rotary electric contacts associated with each dial, one contact of each pair being manually adjustable and the other contact being operated by clock-work, a single clock-driven shaft for simultaneously operating all of said other contacts, whereby the manual adjustment of the first-named contact of any dial determines the time at which said contact engages the associated clock-driven contact, means whereby the engagement of a pair of said contacts automatically tunes in the station represented by the corresponding dial, a pair of additional dials carried by said mechanism and having each a manually adjustable pointer to indicate the time, contact means associated with said additional dials for causing the connected radio receiver to be automatically turned on and off at the respective times indicated by the pointers of said additional dials.

7. The combination of a radio receiver having variable tuning elements, a rotary shaft for actuating said elements an electric motor for operating said shaft, clock-controlled mechanism for automatically energizing said motor at a predetermined time to operate said shaft to any one of a plurality of preselected tuning positions, said mechanism including a switch and a finger piece for each station, each finger piece being selectively operable to cause automatic closing of the associated switch by said mechanism at a time when a preselected station shall be tuned in, there being connections whereby any closed switch energizes said motor, a device controlled by said clock-controlled mechanism for recording the program of a tuned-in station, and means whereby any finger piece is manually adjustable to prevent closing of the associated switch by the clock-controlled mechanism, which is thereby rendered ineffective to tune in the station represented by the adjusted finger piece, each finger piece being also adjustable to close the associated switch at any time so as to tune in instantly the corresponding station independently of the clock movement of said mechanism.

ADOLPH A. THOMAS.
